UNITED STATES PATENT OFFICE.

HARRY HERMAN SCHUTZ, OF LOS LUNAS, NEW MEXICO.

PLUG-TOBACCO CUTTER.

1,212,118.

Specification of Letters Patent.

Patented Jan. 9, 1917.

Application filed January 27, 1916. Serial No. 74,632.

To all whom it may concern:

Be it known that I, HARRY H. SCHUTZ, a citizen of the United States, and a resident of Los Lunas, in the county of Valencia and State of New Mexico, have invented a new and Improved Plug-Tobacco Cutter, of which the following is a full, clear, and exact description.

Objects of my invention are to provide 10 a cutter that may be cheaply produced in compact form to include a base plate having an ample area to firmly support thereon a piece of plug tobacco, and also a knife especially adapted to cut a piece from the 15 plug of tobacco.

The details of construction, arrangement, and operation of the parts constituting my improved cutter are as hereinafter described.

Other objects and advantages of my improved device will be understood from the 20 specific description following.

Reference is to be had to the accompanying drawings forming a part of this specification in which similar reference characters 25 indicate corresponding parts in all the views.

Figure 1 is a perspective view of a cutter embodying my invention, the knife being shown raised; Fig. 2 is a perspective view 30 of the cutter showing the same in the lowered position after severing a piece from the tobacco plug; Fig. 3 is a transverse vertical section on the line 3—3, Fig. 2, showing a tobacco plug in position to be cut; and Fig. 4 is a similar view with the tobacco 35 plug removed.

In producing a cutter in accordance with my invention, a flat base plate 10, of sheet metal, is provided, adapted to afford ample 40 surface on the upper side thereof to receive and support a piece of plug tobacco A. The base is made generally of oblong form and may have the forward end thereof rounded as at 10^a. One corner of the plate 10 is upturned to provide an upstanding hinge lug 11 to which the cutter, designated generally by the numeral 12, is pivoted by a rivet 13, or the like, so that the cutter may swing in a vertical plane toward and from the base plate 10.

The cutter 12, like the base 10, is stamped

up from sheet metal and includes elements particularly adapting it for the special purpose. Thus, in cross section the cutter is made angular or L-shaped to constitute the 55 vertical knife 14 and the integral back plate 15 at right angles to the knife or substantially so. The position of the lug 11 is such as to cause the knife 14 to swing in a vertical plane at such a distance from the 60 adjacent longitudinal edge of the base 10 as to sever a small piece a, Fig. 2, from the plug A at the end, when the knife is brought down parallel with the base 10.

The forward or free end of the knife 14 65 is bent laterally as at 16 beneath the back plate 15, inward from the free end of the latter so as to brace and strengthen said back plate and serve also as a stop for the cutter when pressed down. In using the device, pressure is applied to the broad back 70 plate 15, thus forcing the knife down through the tobacco plug and severing a piece of the same.

It will be observed more particularly from 75 Fig. 4 that the lateral back member 15, when the cutter is in the lowered position, extends beyond or overhangs the adjacent edge of the base plate 10, by reason of which arrangement the said edge of the base plate 80 constitutes a gage for the plug and when the knife is lowered and the piece a severed the back plate will project sufficiently beyond the plug to be engaged by the fingers, and the knife thus be conveniently raised. 85

Having thus described my invention I claim as new and desire to secure by Letters Patent:

1. An improved cutter for plug tobacco comprising a flat metal base, one corner of 90 the same being upturned and constituting an upstanding hinge lug, an angle iron cutter consisting of a vertical knife member and a lateral back member formed integrally, the said knife member being pivoted 95 at one end to said lug and its free end bent laterally beneath the back member and inward from the free end of the knife, as and for the purpose specified.

2. A tobacco-plug cutter comprising a 100 sheet metal base plate adapted to support a tobacco plug, and a cutter hinged at one

end to said base plate at the corner of the same, the cutter being in the form of an angle iron and presenting a vertical knife member and a lateral back member which is integral therewith, the knife member being provided at its free end with a stop, as and for the purpose specified.

In testimony whereof I have signed my name to this specification in the presence of two subscribing witnesses.

HARRY HERMAN SCHUTZ.
